UNITED STATES PATENT OFFICE.

JOHN M. ETIMAN, OF MAPLETON, NORTH DAKOTA.

GRAIN-CAR DOOR.

1,359,344.

Specification of Letters Patent. Patented Nov. 16, 1920.

Application filed May 17, 1919. Serial No. 297,881.

To all whom it may concern:

Be it known that I, JOHN M. ETIMAN, a citizen of the United States, residing at Mapleton, in the county of Cass and State of North Dakota, have invented new and useful Improvements in Grain-Car Doors, of which the following is a specification.

This invention relates to improvements in car doors of a type used in connection with cars for hauling grain, coal or like material.

One of the objects of the invention is to provide a door made up of sections with means for quickly and easily connecting the sections to the door post of the car by bolts and pins located in said post.

Another object of the invention is to provide a supplemental door for the lower part of the doorway which is made over the supplemental door, shown in Letters-Patent #1,125,826 granted to me on January 19, 1915.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Fig. 1 is a view of my improved door looking from the inside of the car;

Fig. 2 is a front view of the door sections;

Fig. 3 is a section on line 3—3 of Fig. 1;

Fig. 4 is a section on line 4—4 of Fig. 1;

Fig. 5 is a plan view of the supplemental door in open position.

Fig. 6 is a detail view showing the bolt receiving means in one edge of the door.

In these views 1 indicates the roof of the car, 2 the floor and 3 the side of the car provided with a door opening 4. At each side of the door opening 4 are located the door posts 5. At suitable points on one post I locate the pins 6 and on the other post I locate bolts 7 which are provided with enlarged heads. The door is composed of the independent sections 8 and the supplemental section 9. The sections 8 are each provided with a metal binding strip 10 of an angle shape which engages one face and the

end of the door and a like strip 11 is located at the other end of the section. One of these strips is provided with a slot 12 which extends into both flanges thereof and immediately under this slot the section is cut away to provide a recess 13. This slot and recess are to receive the bolt 7 so as to hold this end of the section to the door post. The other end of the section is provided with a hole 14 which passes through the metal strip and this hole is to receive the pin 6. The section is then held in engagement with the pin and bolt by means of the hook 15 carried by the door post and engaging the upper edge of the section. I may locate a metal strip 16 a suitable distance from the strip 11 and form a hole 17 in this strip and the section to receive the pin 6 so as to make the section fit different widths of door openings.

It will, of course, be understood that when desired, a number of slots and holes may be formed in each section to engage the bolts and pins on the door post. Each section is provided with an upright 18 at each end and the bottom of each upright projects below the bottom of the section while its upper end is spaced from the top edge of the section so that these uprights will overlap the adjacent sections when the sections are in place. Small spaces may be left between the ends of these uprights to receive each of the hooks.

The metal strips at the edges of the sections will prevent the sections from being nailed to the post, in addition to acting as strengthening means for the sections.

The supplemental section 9 is composed of a long strip 19 and a short strip 20, the strips being of such a length that the short strip will fit between the two posts, while the long strip will overlap said posts. Thus longitudinal movement of the supplemental door is prevented. The long strip is formed of a short piece 21 and a long piece 22 which are hinged together by the hinge 23. The short strip is also formed of a long and short piece 24 and 25, the short piece 24 being secured to the long piece 22 while the long piece 25 is secured to the short piece 21. The two pieces 24 and 25 are adapted to be secured together by the latch means 26. The short strip 20 is of greater width than the long strip 19 so that said short strip will overlap the section 8 of the door which has its lower edge resting on the long strip.

It will be seen that when a car is to be entered the latch is swung away from its keeper so as to free one part of the short strip from the other. The pressure of the material within the car will then force the section 22 outwardly and thus move the entire supplemental door out of the door opening to permit the passage of the material from the space below the door sections.

10 It is thought from the foregoing description that the advantages and novel features of my invention will be readily apparent.

I desire it to be understood that I may make changes in the construction and in the 15 combination and arrangement of the several parts, provided that such changes fall within the scope of the appended claim.

What I claim is:—

The combination with a car having a door

opening therein and door posts at the side 20 walls of said opening, of a door section, metal strips of angle form located on one face of the section adjacent the ends thereof with their flanges engaging the ends, one of said strips having an opening therein and 25 the other strip having a wide slot in its end flange and a narrow slot in the other flange, said slots being connected together and the section having a recess registering with said slots, a bolt on one post adapted 30 to engage with the opening, a bolt on the other post adapted to engage with the slots and recess and hooks carried by the door post for engaging the end of the section which carries the opening for the beam. 35

In testimony whereof I affix my signature.

JOHN M. ETIMAN.
